UNITED STATES PATENT OFFICE.

CHARLES DEWITT MCNEILL, OF GOLIAD, TEXAS.

HAY-PRESS.

SPECIFICATION forming part of Letters Patent No. 366,233, dated July 12, 1887.

Application filed April 8, 1887. Serial No. 234,175. (No model.)

To all whom it may concern:

Be it known that I, CHARLES DEWITT MCNEILL, a citizen of the United States, residing at Goliad, in the county of Goliad and State of 5 Texas, have invented certain new and useful Improvements in Hay-Presses; and I do hereby declare the following to be a full, clear, and exact description of the invention, such as will enable others skilled in the art to which it app- 10 pertains to make and use the same.

This invention relates to certain new and useful improvements in baling-presses designed more especially for compressing hay for baling, and while it pertains more particu- 15 larly to horizontal toggle-presses, some of the novel features will be found fully as applicable to other styles.

The invention aims at simplicity and cheap- 20 ness of construction and ease and efficiency in operation.

To these ends and to such others as the invention may pertain, the same consists in the particular construction, arrangement, and adaptation of parts, all as more fully herein- 25 after described, shown in the drawings, and then specifically defined by the claims.

In the accompanying drawings forming a part of this specification, Figure 1 represents a top plan of the press constructed in accordance with my invention. Fig. 2 is a side elevation of same. Fig. 3 is a plan view with parts in a horizontal section and parts removed to show interior of press. Fig. 4 is a side elevation of the press, part in vertical section, 35 with parts removed. Figs. 5 and 6 represent, in detail perspective, the follower and long levers. Fig. 7 represents detailed views of clamps.

Referring to the details of the drawings, A 40 designates a suitable frame or sill supporting the base-plate B, which forms the bottom of the feed-box and press chamber, the former of which is also provided with two sides and top, supported by the cross-bars *a* and uprights *b*, the upper ends of which uprights are preferably joined by brace or tension rods *c*, which serve to prevent the spreading of the same during the operation of the press. The feed- 45 box is open at both ends, the rear end com- 50 municating with the press-chamber and the other receiving the plunger or follower-block C. This follower-block is attached to the rear

end of a guide-plate, D, provided at its forward end with a clevis or other suitable means, to which is attached the rope or chain *d*, 55 the free end of which is preferably provided with a handle, *e*. This guide-plate is guided by the strips *f*, attached to the base-plate B, and having their forward ends preferably rounded, as shown. To this guide-plate, preferably within a recess, *g*, therein, are pivoted upon a common pivot the long levers E, the pivoted ends of which are halved out, as shown in Figs. 4 and 6, to allow the said levers to move on the same horizontal plane. The 60 shoulders formed by halving serve as stops to limit the inward movement of the long levers, and may thus indicate when the plunger has moved its full stroke. The free ends of these levers are bifurcated, and in these bifurcations 65 are journaled the pulleys *h*. To these levers, at a point between their center and their rear ends, are pivoted one end of the short levers F, the opposite ends of which are pivoted on pivots *i*, to a plate, G, secured to the frame A, 70 to which plate is also secured a guide, *k*, for the rope *d*. Near the free end of one of the levers E is rigidly secured one end of the rope or chain *H*, the other end of which passes around the pulley on the end of the other long 75 lever, thence back to and around the pulley on the lever to which its other end is attached, and thence to the source of power. (Not shown.) The rear end of the press-chamber is braced by braces *l*, and upon its inner face is provided with a head-block, I, formed with longitudinal grooves *m*, the object of which, and of corresponding grooves, *n*, in the follower-block, will soon be explained.

The sides and top of the press-chamber are 80 made removable, and are secured in position in the following manner: Secured to the frame A in the proper position are the pieces K, formed with sockets *o*, which engage the extended ends *p* of the cleats L on the side M of 85 said chamber, it being understood that the two sides are constructed and secured in position in the same manner. The top of this chamber is also provided with cleats *r*, connected at one end by the cross-bar *s*, while the other 90 ends of said cleats removably engage sockets *t* in the rear cross-bar of the top of the feed-box. To hold the sides and top in position I use two 95 clamping-bars, O P, the former provided at

each end with a lug, *u*, which lugs embrace the cross-bar *s* on the top of the chamber and a cross-bar, *v*, secured to the rear face of the rear end of said chamber, while the other 5 clamping-bar, (shown in detail in Fig. 7,) is formed with five lugs, *w*, the outer ones of which are slightly longer than the others, and engage the spaces formed between the cleats *L* on the sides of the chamber, while the other 10 lugs engage the spaces between the cleats *r* on the top and between said cleats and the sides. It will be observed that the plate or block *D* extends through the end of the feed-box, so 15 that the long levers connected thereto will play in the end of the box, instead of through the sides of the box, when the follower is thrown forward to compress the hay in the press-chamber.

The operation is simple. Power is applied 20 to the rope *d*, which will cause the levers and plunger to assume the position indicated by dotted lines in Fig. 3. The clamping-bars *O* *P* are then removed and the top of the press-chamber taken off. The material to be baled 25 is then put in and pressed in the feed-box till the press is full. The top of the press-chamber is then replaced, the clamping-bars *O* *P* secured in place, and power applied to the rope *H*. A continuance of the power forces the parts into 30 the position indicated by full and dotted lines in Fig. 2. The short levers coming in contact with the forward ends of the guide-strips *f*, serve to limit their movement, and thus indicate that the material is pressed. The clamping-bar *P* and the sides *M* are then removed, 35 and the wires or ties run through the grooves *m* *n* and around the bale and made fast, when the other clamping-bar and the top are removed, and the bale is then free to be taken 40 out and the operation repeated.

Material may be fed directly into the feed-box by making its top removable, and other changes may be made in the details of construction without departing from the spirit of 45 my invention.

Having described my invention and set forth its merits, what I now claim is—

1. The combination, with the follower-block and guide-plate attached thereto, of the guide-strips for said plate, the long levers pivotally 50 secured to said guide-plate, and the short levers pivotally connecting said levers and

frame and limited in their movement by said strips, as set forth.

2. The combination, with the frame, the 55 follower-block, and the guide-plate attached thereto, of the long levers pivoted at one end to said guide-plate, the short levers pivoted at one end to said frame at a point intermediate of the outer and inner ends of the two 60 long levers and at the other end to said levers, pulleys carried by the free ends of said long levers, a stop to limit the inward movement of the long levers, and the operating-cord connecting said free ends, substantially as 65 described.

3. The combination of the press-chamber, the covered feed-box between the press-chamber and operating-levers, the follower-block normally lying within the feed-box and having 70 a plate, *D*, extending therefrom, the long levers pivoted to said plate to work through the end of the feed-box, the short levers pivoted at one end to the frame of the machine at a 75 point between the outer and inner ends of the long levers and at the other end to the long levers, and an operating-cord connecting the free ends of the long levers, substantially as described.

4. The combination, with the press-chamber having removable top and sides, of a clamping-bar having lugs to embrace said sides and to secure said sides in place, substantially as described.

5. The combination, with the feed-box provided with cross-bar having sockets, as described, of a removable top to the press-chamber provided with cleats engaging said sockets and clamping-bars for holding said top in position, as set forth.

6. The combination, with the frame provided with sockets *o*, braces *l*, and cross-bar *v*, and the feed-box provided with sockets *t*, of the removable sides and top to the press-chamber, provided with cleats to engage said 95 sockets, and the removable clamping-bars *O* *P*, provided with lugs, substantially as and for the purpose specified.

In testimony whereof I affix my signature in presence of two witnesses.

CHARLES DEWITT McNEILL.
